DESIGN FOR A CAMERA DOLLY

Herbert W. Houston, Sherman Oaks, Calif., assignor to The Houston Corporation, Los Angeles, Calif., a corporation of California

Application November 18, 1946, Serial No. 134,860

Term of patent 3½ years

(Cl. D14—3)

To all whom it may concern:

Be it known that I, Herbert W. Houston, a citizen of the United States and resident of the city of Sherman Oaks, county of Los Angeles, State of California, have invented a new, original, and ornamental Design for a Camera Dolly, of which the following is a specification, reference being had to the accompanying drawings, forming a part thereof, in which:

Fig. 1 is a view in perspective of a dolly embodying the present invention;

Fig. 2 is a plan view of the dolly shown in Fig. 1; and

Fig. 3 is a view in side elevation of the dolly shown in Figs. 1 and 2.

I claim:

The ornamental design for a camera dolly, substantially as shown.

HERBERT W. HOUSTON.
